UNITED STATES PATENT OFFICE.

OTIS R. ANGELL, OF BOSTON, MASSACHUSETTS.

SELF-LIGHTING GAS-LIGHTER.

1,111,939.

Specification of Letters Patent. Patented Sept. 29, 1914.

Application filed January 22, 1914. Serial No. 818,758.

To all whom it may concern:

Be it known that I, OTIS R. ANGELL, a citizen of the United States, residing at Boston, in the county of Suffolk and State of Massachusetts, have invented certain new and useful Improvements in Self-Lighting Gas-Lighters, and I do declare the following to be a full, clear, and exact description of the invention, such as will enable others skilled in the art to which it appertains to make and use the same.

This invention relates to self-lighting apparatus for gas lighting purposes in which an igniting device is employed of the class wherein a spark or sparks are produced by striking small particles from one substance by the abrasive action of another substance. Such devices operate upon the principle of the flint and steel, inasmuch as the spark or 20 sparks are produced by the removal from a material similar in its nature to flint of minute particles which are heated to near incandescence by their sudden removal from the flint like substance when the steel like 25 member abrades or rubs upon the point or pencil of the material.

The object of the invention is to provide a torch of this character in which a lamp is simultaneously lighted and projected from 30 its protective casing.

With this and other objects in view, the invention consists of certain novel features of construction, and the combination and arrangement of parts, as will be more fully 35 described and claimed.

In the accompanying drawings: Figure 1 represents a longitudinal section of a gas lighting torch constructed in accordance with this invention; Fig. 2 is a top plan 40 view thereof; Fig. 3 is a transverse section taken on line 3—3 of Fig. 1; Fig. 4 is a longitudinal section of another form of the invention with the supporting and actuating rods broken off; Fig. 5 is a vertical section 45 on the line 5—5 of Fig. 4; Fig. 6 is a side elevation of another form of the invention; Fig. 7 is a longitudinal section taken on the line 7—7 of Fig. 8; Fig. 8 is a top plan view thereof; Fig. 9 is a transverse section taken 50 on line 9—9 of Fig. 7.

In the embodiment illustrated in Figs. 1, 2 and 3, a casing 1 is shown constructed of any suitable material and open at one side thereof to provide for the outward swing- 55 ing of the lamp 2, which is pivotally mount-

ed at one end or corner as shown at 3, in said casing. This lamp 2 has a wick 4 projecting beyond its free end and a protective shield 5 arranged adjacent said wick to protect the flame of the lamp when it is swung outwardly into operative position. This casing 1 is preferably open also at its upper end to provide for the reciprocation of the igniter actuating device, as will be described. As shown, this casing 1 is mounted on a supporting rod 6 having a suitable handle 7 which may be grasped by the operator when the device is used for lighting street lamps or for other purposes, and this supporting rod 6 has laterally extending 70 loops 8 at intervals thereon, forming guides for an actuating rod 9 having a finger hold or grip 10 at its lower outer end. This rod 9 extends into the casing 1 and the free end thereof is connected with the lamp 2 by a 75 link 11, said link being connected at one end with the lamp mid-way its length and at its other end with the free end of the rod. 9. A steel disk 12 is revolvably mounted in the casing 1 adjacent the wick 4 of the lamp 80 when said lamp is in normal or retracted position and secured to one face of this disk is a ratchet wheel 13.

A ratchet bar 14 is pivotally mounted at 85 one end on the rod 9 at a point within the casing and one edge of this bar 14 is toothed and positioned to engage the teeth of the ratchet wheel 13, being held in engagement therewith by a coil spring 15 which encircles the rod 9 within the casing 1, bearing 90 at one end on the lower end of said casing, and at its other end on said bar 14, whereby the bar is held normally in projected position, as shown clearly in Fig. 1, ready to be moved downwardly for turning the ratchet 95 wheel and the disk carried thereby. A leaf spring 16 is shown arranged between the rear edge of said bar 14 and the adjacent wall of the casing 1 and exerts its tension 100 to hold said bar yieldably in engagement with the ratchet wheel 13. A tube 17 extends at an oblique angle into said casing with its inner open end disposed adjacent the periphery of the steel disk 12, said periphery being roughened for a purpose to be described. Mounted in this tube 17, is a piece of sparking metal 18, which is normally pressed outward into engagement with the periphery of the disk 12 by means 105 of a coil spring 19 mounted in the tube 17 110

between the closed outer end thereof and the inner end of the sparking metal 18. A cap 20 closes the outer end of the tube 17 having a threaded engagement therewith and being 5 adjustable thereon for varying the tension of the spring 19.

In the operation of this device, the handle 7 being grasped in one hand of the operator, the loop 10 on the rod 9 has one of the operator's fingers inserted therein, either of the hand which grasps the handle 7 or the other hand, as may be most convenient, and said rod is moved outwardly toward the handle 7, thereby causing the rack bar 14 to be drawn 15 inwardly into the casing 1 which movement causes the ratchet wheel 13 and the disk 12 carried thereby to be rapidly rotated and the periphery of said disk being in contact with the sparking metal 18 produces a series 20 of sparks which lights the wick 4 of the lamp 2 disposed adjacent thereto. Simultaneously with this actuation of the igniting device, the lamp 2 is swung outwardly from the casing 1 through the open side thereof 25 by means of the link 11, which, on the inward movement of the rod 9 in said casing, straightens or moves into a lateral position substantially at right angles to said rod 9, thereby forcing the lamp 2 outwardly, causing 30 it to swing on its pivot 3 outwardly into a position beyond the casing 1. The torch is then ready for use. After the torch has been used and it is desired to retract the lamp 2 within the casing 1, the loop 10 of the rod 9 is released and the spring 15 in the casing 1 will force said rod upwardly into 35 said casing, thereby forcing the bar 14 outwardly and link 11 into oblique position shown in Fig. 1, whereby the lamp is moved 40 into the casing and completely housed thereby.

It will thus be seen that this device, while being very simple, may be quickly operated for lighting and simultaneously projecting 45 the lamp by a simple pull exerted on the rod 9 and on the releasing of said rod, the parts will be automatically returned to inoperative or normal position.

In the form shown in Figs. 4 and 5, a 50 casing 1' is shown similar in construction to the casing 1 of the figures above described, and having a lamp 2' pivotally mounted therein and adapted to swing outwardly through an opening in one side wall thereof, 55 said lamp being pivoted at one corner as shown at 3'. This lamp 2' is provided with the usual wick 4' which is disposed adjacent to an igniting device here shown in the form of a steel disk 12' having its peripheral edge beveled on one face thereof as shown at 12''. This disk 12' is fixed to a sleeve 21 revolvably mounted on a shaft 22 mounted in the opposite side walls of the casing 1'. A piece of 60 sparking metal in the form of a pencil 18' is 65 mounted in a tubular casing 17, similar to

that shown in the other figures, with its free end projecting beyond said casing into engagement with the beveled edge of the steel disk 12'. This pencil 18' is normally projected outwardly by a coil spring 19' arranged in the casing 17' and the tension of which is controlled by an adjustable cap 20' in a manner similar to that above described.

A ratchet wheel 13' is fixed to the sleeve 21 adjacent one wall of the casing 1 and 70 spaced slightly from the disk 12'. Said ratchet wheel when revolved will cause the revolution of the sleeve 21 and the disk 12', secured thereto, so as to produce an abrading effect on the pencil 18' and thereby causes 75 80 85 90 95 rack bar 37 and at its other end with a lever 41 fulcrumed intermediately of its ends on the wrench 30, the other end of said lever being pivotally connected with the upper 5 or outer end of an actuating rod 42 which is mounted to slide in guides as 43 carried by the wrench. A coil spring 44 encircles the rod 42 bearing at one end on the outermost 10 guide 43 and at its other end on the lever 41, whereby said lever is normally held in position to retract the ratchet bar 37 and position it ready for projection on the pulling of the rod 42 to turn the ratchet wheel 36 for rotating the disk 35 in contact with the 15 sparking pencil 34 and thereby light the wick of the lamp 29, which is arranged adjacent said sparking device.

The link 11 which connects the lamp with the actuating rod in the form shown in Figs. 20 1 to 5 has a slotted connection with the said rod, the pins 9" and 23 which connect them in both forms being slideable in the slot 11' in said link to permit the actuating rod to move a predetermined distance for revolving 25 the disk to produce a spark, before moving the lamp outward, thus permitting the lamp wick to be lighted before the lamp is projected, the preliminary movement of the actuating rod being controlled by the length 30 of the slot 11'.

I claim as my invention:

1. A gas lighting torch comprising a casing open at one side, a lamp pivotally mounted in said casing to swing out through 35 said open side, an igniting device arranged in said casing adjacent the wick of said lamp and means for simultaneously actuating said igniting device and ejecting said lamp from said casing.
2. A gas lighting torch comprising a casing, a lamp pivoted in said casing to swing outwardly therefrom, a reciprocable member mounted in said casing, a link connecting said member with said lamp, a sparking 45 pencil also arranged in said casing, an abrading member arranged in contact with said pencil and means connected with said reciprocable member for simultaneously ac-

tuating said abrading member and projecting said lamp.

3. A gas lighting torch comprising a casing, a lamp pivotally mounted in said casing to swing outwardly therefrom, a rod extending into said casing, a ratchet bar pivotally connected at one end to said rod, a coil 55 spring arranged on said rod between one end of said casing and said bar for normally projecting said bar, a sparking pencil arranged in said casing, an abrading disk positioned to engage said pencil and having a ratchet wheel fixed to one face thereof in position to be engaged by the teeth of said ratchet bar, means for yieldably holding said bar in engagement with said wheel, and means connecting said lamp with said rod 65 whereby the lamp is simultaneously projected on the actuation of the igniting device when a pull is exerted on said rod.

4. A gas lighting torch comprising a casing open at one side, a lamp pivotally mounted in said casing to swing outward through said open side, an igniting device arranged in said casing adjacent the wick of said lamp and comprising a revolvably mounted abrading disk having a ratchet 75 wheel fixed to one face thereof, a tube extending obliquely into said casing and having its inner end open and arranged adjacent the periphery of said abrading disk, a 80 sparking pencil mounted in said tube, a spring for normally projecting said pencil into engagement with said abrading disk, and a cap screwed on the outer end of said tube for controlling the tension of the spring which projects said sparking pencil, and 85 means engaged with said ratchet wheel for simultaneously turning said disk and projecting said lamp.

In testimony whereof I have hereunto set my hand in presence of two subscribing witnesses.
